US00D971038S

(12) **United States Design Patent** (10) Patent No.: **US D971,038 S**
(45) Date of Patent: **** Nov. 29, 2022**

(54) **LEVEL INDICATOR FOR SURVEY**

(71) Applicant: **Topcon Corporation**, Tokyo (JP)

(72) Inventor: **Mitsuo Ishii**, Tokyo (JP)

(**) Term: **15 Years**

(21) Appl. No.: **35/512,321**

(22) Filed: **Feb. 2, 2021**

(80) **Hague Agreement Data**

Int. Filing Date: **Feb. 2, 2021**

Int. Reg. No.: **DM/212700**

Int. Reg. Date: **Feb. 2, 2021**

Int. Reg. Pub. Date: **Aug. 6, 2021**

(51) **LOC (13) Cl.** **10-04**

(52) **U.S. Cl.**

USPC **D10/69**

(58) **Field of Classification Search**

USPC D10/70, 81, 78, 106.1, 46, 80, 47, 103, D10/56, 52, 53, 65, 77; D13/199

Primary Examiner — George D. Kirschbaum

Assistant Examiner — Antoinette Martine Suiter

(57) **CLAIM**

The ornamental design for a level indicator for survey, as shown and described.

DESCRIPTION

1. Level indicator for survey

1.1 : Perspective

1.2 : Perspective

1.3 : Front

1.4 : Top

1.5 : Bottom

1.6 : Right

1.7 : Left

1.8 : Back

(Continued)

The broken lines represent portions of the article that form no part of the claimed design.

1 Claim, 8 Drawing Sheets
